US0D1045183S

(12) **United States Design Patent** (10) **Patent No.:** **US D1,045,183 S**
(45) **Date of Patent:** **** Oct. 1, 2024**

(54) **CRYSTAL SOLAR LIGHT**

(71) Applicant: **E. MISHAN & SONS, INC.**, New York, NY (US)

(72) Inventor: **Steven Mishan**, New York, NY (US)

(73) Assignee: **E. MISHAN & SONS, INC.**, New York, NY (US)

(**) Term: **15 Years**

(21) Appl. No.: **29/932,223**

(22) Filed: **Mar. 12, 2024**

Related U.S. Application Data

(62) Division of application No. 29/883,714, filed on Feb. 2, 2023, now Pat. No. Des. 1,026,298.

(57) **CLAIM**

The ornamental design for a crystal solar light, as shown and described.

DESCRIPTION

FIG. 1 is a top, right, side perspective view of a crystal solar light showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the crystal solar light is for the purpose of illustrating portions of the article that form no part of the claimed design.

1 Claim, 6 Drawing Sheets
